UNITED STATES PATENT OFFICE.

FREDERICK JAMES NORRIS, OF FALL RIVER, MASSACHUSETTS, ASSIGNOR TO BARNARD MANUFACTURING COMPANY, OF FALL RIVER, MASSACHUSETTS, A CORPORATION OF MASSACHUSETTS.

LOOM.

Application filed February 27, 1924. Serial No. 695,489.

To all whom it may concern:

Be it known that I, FREDERICK J. NORRIS, a citizen of the United States, residing at Fall River, in the county of Bristol and 5 State of Massachusetts, have invented new and useful Improvements in Looms, of which the following is a specification.

This invention relates particularly to the intermediate mechanism which connects the 10 lay-operating crank-shaft of a loom with the usual jumper mechanism, said intermediate mechanism being adjustable to permit variations in the timing of the movements of the heddles relative to those of 15 the lay.

Heretofore said intermediate mechanism has included an arm having a hub adjustably secured by a set screw or screws to the crank-shaft and connected by a connecting- 20 rod with an oscillatory element of the jumper mechanism. This intermediate mechanism is objectionable, because the arm is liable to become loose on the crank-shaft.

One object of the invention is to provide 25 an improved adjustable intermediate mechanism obviating the above-mentioned objection.

Another object is to improve the construction of the oscillatory element of the jumper 30 mechanism in such manner as to provide an improved connection between said element and the usual hooked rods constituting elements of the connections between the oscillatory element and the heddles, said rods 35 being moved as usual in one direction by the oscillatory element, and in the opposite direction by the usual dobby levers, the improved connection obviating certain objections hereinafter stated to the connection 40 ordinarily provided.

Of the accompanying drawings forming a part of this specification,—

Figure 1 is a side view, showing a portion 45 of a loom embodying my improvements.

Figure 2 is a fragmentary end view, a portion of the frame being shown in section.

Figure 3 is an enlargement of a portion 50 of Figure 1.

Figure 4 is a section on line 4—4 of Figure 50 3.

Figure 5 is a side view, showing separately the hub shown by Figures 3 and 4.

Figure 6 is a fragmentary perspective 55 view, showing portions of the jumper mechanism.

The same reference characters indicate the same parts in all of the figures.

12 designates the crank-shaft of a loom connected as usual, with the lay 13, by a rod 14. The heddles 15 are operated as 60 usual, by a jumper mechanism and a dobby mechanism. The jumper mechanism includes an oscillatory element, comprising a rock-shaft 16, having at one end an arm 17, engaged with a connecting-rod 18, 65 through which oscillatory motion is imparted to said element from the crank-shaft, and a pair of spaced apart arms 17^a, arranged at an angle to the arm 17. The jumper mechanism also includes rods or 70 wires 19, having hooks 20, engaged with a cross-bar 21, connecting the arms 17^a. There are as many rods 19 as there are heddles, only one rod being shown by Figure 6. Each rod is provided with a slot 22, engaging a 75 lever 23 (Figure 2) of the dobby mechanism. Each rod is connected by a flexible strap 24 with the corresponding heddle, the straps passing over pulleys 25.

The mechanism as above described, is well 80 known, and involves nothing new with me, excepting the form of the bar 21, and the means connecting the rod 18 with the crank-shaft, as hereinafter described. It is therefore unnecessary to describe the operation 85 of a loom including said mechanism.

To the crank-shaft is fixed, as by a key 26, (Figure 4), a holder 27, formed as a disk or wheel surrounding the shaft.

A hub 28 is rotatively adjustable on the 90 crank-shaft and holder, means being provided for positively securing the hub to the holder in any position to which the hub may be rotatively adjusted. In this instance, the holder 27 is provided with clamping 95 studs 30, passing through arcuate slots 32 in the hub, the studs having heads 31, adapted to exert a clamping pressure on the hub. Said heads may be integral with the studs, the latter being screwed into tapped orifices 100 in the holder, or the studs may be otherwise fixed to the holder, the heads being clamping nuts engaged with threaded portions of the studs.

The hub is provided with an eccentric 105 wrist-pin 34, preferably inserted in an eccentric boss 35, formed on the hub, the boss having a recess receiving the head 36 of the wrist-pin, and a slot 35^a through which the pin projects, as shown by Figure 4. A nut 110

37 on the wrist-pin confines an enlarged end of the connecting-rod 18 on the wrist-pin. The opposite end of the rod 18 is pivoted to the arm 17 at 38.

5 The boss 35 offsets the wrist-pin and the connecting-rod from the body of the hub. The holder 27 is preferably provided with an annular hand grip 39, connected with the body of the holder by arms 40, so that 10 the crank-shaft may be manually rotated. It is common to provide a hand wheel for this purpose as a separate member. I have departed from the usual practice in this respect by utilizing the holder 27 constituting 15 an element of adjustable connecting mechanism, as an element of a hand wheel.

The holder 27, the hub 28 rotatively mounted on the holder, and provided with the wrist-pin 34, the connecting-rod 18, and 20 the means for positively confining the hub to the holder in various adjusted positions, constitute a reliable adjusting mechanism whereby the movements of the jumper mechanism may be timed or varied with relation 25 to those of the lay, said mechanism being free from liability to become accidentally loosened and inoperative.

Heretofore each of the hooked rods 19 of the jumper mechanism has been connected with a bar extending between the 30 rock-shaft arms 17, by a leather strap engaged at one end with the hook 20, and secured at the other end to the bar by a screw. These straps are flexible and cause an uneven or jerky action of the jumper mechanism which is objectionable.

Another objection is the weakness of the straps, causing more or less breakage at the end portions, and loss of time. To obviate 40 these objections I elongate the rods 19, so that their hooks 20 directly engage the bar 21, as shown by Figure 6. The hooks are 45 slidable on the bar, and the rods are spaced apart by peripheral corrugations or ridges 42, formed on the bar, as shown by Figure 6.

I claim:

1. An adjustable intermediate mechanism, 50 adapted to connect the lay-operating crank-shaft with the jumper mechanism of a loom, said mechanism comprising a holder fixed to the crank-shaft, a hub mounted for rota-

tive adjustment on the holder, and provided with an eccentric wrist-pin, confining means for positively securing the hub to the holder in any position to which the hub may be 55 rotatively adjusted, and a rod connecting said wrist-pin with an oscillatory element of the jumper mechanism.

2. An adjustable intermediate mechanism 60 substantially as specified by claim 1, the said holder being provided with clamping studs passing through arcuate slots in the hub, and adapted to positively secure the hub to the holder in any position to which the hub 65 may be rotatively adjusted.

3. An adjustable intermediate mechanism substantially as specified by claim 1, said holder being provided with an outwardly 70 projecting eccentric boss supporting said wrist-pin offset from the holder and from the body of the hub.

4. An adjustable intermediate mechanism substantially as specified by claim 1, said holder being provided with an outwardly 75 projecting eccentric boss supporting said wrist-pin offset from the holder and from the body of the hub, the holder being provided also with an annular hand grip spaced from the connecting-rod, and permitting 80 manual rotation of the crank-shaft.

5. A loom which includes a lay-operating crank-shaft, a dobby mechanism, jumper mechanism including an oscillatory element, 85 adjustable means connecting the crank-shaft with the element to oscillate the latter, said means including a connecting-rod, and a plurality of hooked rods constituting elements of connections between the oscillatory element, the dobby mechanism, and the heddles, the said element comprising a rock-shaft having an arm engaged with the connecting-rod, a pair of spaced apart arms fixed to the rock-shaft and arranged at an angle to the rod-engaging arm, and a bar 95 connecting said spaced apart arms and provided with a plurality of peripheral corrugations directly engaging the hooks of said hooked rods and spacing the rods apart, the hooks being slidable on the corrugated bar. 100

In testimony whereof I have affixed my signature.

FREDERICK JAMES NORRIS.
